(57) **CLAIM**

The ornamental design for a table clock, as shown and described.

DESCRIPTION

FIG. 1 is a front perspective view of a table clock showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of the table clock showing our new design in a state in which the table clock displays time, date and other information;

FIG. 9 is a left side elevation of the table clock shown in a first folded state;

FIG. 10 is a left side elevation of the table clock shown in a second folded state; and,

FIG. 11 is a left side elevation of the table clock shown in an unfolded state.
